MOTOR BOAT DRIVE AND STEERING
MECHANISM

Harry O. Hedges, Seattle, Wash.

Application May 11, 1936, Serial No. 79,064

4 Claims. (Cl. 115—35)

This invention relates to improvements in propeller drive and steering mechanism for motor boats, and it has reference more particularly to what are referred to in trade as an "inboard-outboard drive", by reason of its having the engine, or motor, located inboard and the propeller and steering mechanism, outboard.

It is the principal object of this invention to provide an improved construction wherein the propelling mechanism is rotatably adjustable, as a unit in either direction for steering and for effecting reverse propulsion of the boat.

It is also an object of this invention to provide an outboard drive of the above character wherein the driving and steering mechanism is hingedly suspended from the boat for rearward and upward swinging from normal position, thereby to avoid possibility of damage thereto should the mechanism contact a rock, log, or other obstruction during forward propulsion of the boat.

Still another object of the invention is to provide an automatic means for locking the propeller mounting and steering mechanism against the upward hinging movement that would result from the driving force of the propeller when the mechanism was turned in its mounting in either direction to an extent whereby it is effective for reverse propulsion.

Still another object of the invention is to provide for the automatic release of the propeller driving clutch and also to provide for stopping the engine in the event that the propeller mechanism should strike an obstruction whereby the mechanism would be swung upwardly from normal driving position.

Still further objects reside in the details of construction and in the combination of parts, and in their mode of operation, as will hereinafter be fully described.

In accomplishing these, and other objects of the invention, I have provided the improved details of construction, the preferred forms of which are illustrated in the accompanying drawings, wherein—

Fig. 1 is a longitudinal, sectional view of an inboard, outboard drive mechanism for motor boats, constructed and applied in accordance with the objects of the present invention.

Fig. 1a is a sectional detail of the locking device.

Fig. 2 is a sectional detail of a part of the clutch releasing means.

Fig. 3 is a vertical, sectional detail, on line 3—3 in Fig. 4, illustrating parts of the steering gear.

Fig. 4 is a detail of the driving and steering gearing as seen from the rear; a part of the housing being broken away for better illustration.

Fig. 5 is a plan view of the locking cam, as mounted on the propeller mechanism.

Fig. 6 is a horizontal section on line 6—6 in Fig. 4 showing parts of the steering gear.

Fig. 7 is a detail of a part of the steering gear connection.

The present construction is of that type designed for various types of motor boats wherein the motor, or engine, is located inside, or inboard, and the propeller and steering mechanism is mounted outboard upon the stern end of the boat.

The present invention contemplates a continuous one way rotation of the propeller wheel, and propulsion of the boat in a reverse direction by a rotary adjustment of the propeller and steering gear bodily about the vertical axis of support, to an extent whereby the propulsion force is opposite to the normal direction. It contemplates also that while the steering and propelling mechanism is normally free for an upward hinging movement to avoid damage in the event that it should strike an obstruction while the boat is moving forward, there shall be a normally inactive locking mechanism which will be moved to a position to retain the driving mechanism against this upward swinging action when the direction of propulsion, relative to the boat, is opposite that for normal forward propulsion.

The invention also contemplates that in the event that the propeller mechanism should engage an obstruction while the boat is moving forwardly, with sufficient force to swing it upwardly, this will operate outwardly to disengage the driving clutch and also stop the motor.

Referring more in detail to the drawings—

Fig. 1 designates the stern end wall of a boat and 2 designates the bottom wall. The present driving and steering mechanism is mounted directly on the stern wall and it comprises a mounting base plate 3 which is fitted flatly against the outside of the stern wall and is secured thereto by the insertion of bolts, as at 4, through the corner portions of this casting, and through the stern wall as will be understood best by reference to Fig. 4. On this base plate 3, which is in the form of a casting, is a forwardly extended bearing portion 5 which projects through an opening provided therefore in the wall 4 to the inside of the boat. This bearing portion serves as a mounting for certain shafts and gearing through which the driving connection is completed between the

engine drive shaft, that is located inboard, and the propeller driving gear, which is outboard.

The propeller is designated at 6 and it will be observed by reference to Fig. 1, that it is mounted by a drive shaft 7 revolubly supported normally in a horizontal position within a supporting housing 8. This housing comprises a vertical tubular shank or mounting portion 8a and at the lower end is formed with an integral forwardly directed rudder forming portion 8b and a propeller guard fin 8c. The mounting and driving shaft 7 of the propeller 6 extends in the plane of the rudder and perpendicular to the axis of the shank 8a.

15 The tubular shank 8a of the housing 8 is revolubly fitted at its upper end within a supporting bearing 10 which is formed as an integral part of a gear housing 11. The gear housing is hingedly suspended from the casting 3 by means of 20 a hinge pin 12 which extends horizontally through hinge ears 5a and 11a formed, respectively, on the base member 3 and housing 11.

In the normal operation of the boat, the housing 11 depends flatly against the flat, vertical 25 surface of the base casting 3 and the axis of the shank 8a of the propeller mounting housing 8 is vertically disposed, as shown in Fig. 1. Keyed on the propeller mounting shaft 7, within the housing 8, is bevel gear 15 and this is operatively in mesh with a bevel gear 16 which in turn, is fixed upon the lower end of a drive shaft 18. This latter shaft is extended co-axially of the shank 8a and is revolubly supported at upper and lower ends in anti-friction bearings designated respectively at 19 and 20. At its upper 30 end, the shaft 18 is equipped with a bevel driving gear 22 and this is in operative mesh with a bevel gear 23 that is keyed on a drive shaft 24 revolubly supported in the housing 11; this latter shaft being disposed at a right angle to shaft 18 and is rotatably supported by anti-friction bearings 25 and 26 located, respectively, at the outer end of the shaft and just rearwardly of the bevel gear 23. The shaft 24 extends at 35 its rearward end from the housing 11 and at that end is equipped with a driving pinion gear 28 adapted to interlock in driving relation with an internal ring gear 27 in a manner presently to be described.

50 By reference particularly to Figs. 1 and 6, it will be observed that there is an external ring gear 30 fixed to the upper end of the tubular shank 8a, coaxially thereof. Operating in mesh with this gear 30 is a smaller gear 31. This latter gear is fixed upon the lower end of a vertically extending shaft 32 revolubly supported in the housing 11, as seen in Fig. 3; there being a supporting bearing 35 carrying the upper end of this shaft, while its lower end is revoluble within a socket 36 formed therefor in the housing. At the upper end of the shaft 32 is a small bevel gear 38 operatively in mesh with a similar gear 39 that is fixed upon a supporting shaft 40 rotatably mounted in a bushing 41 which is fitted within an opening provided therefor in the inner wall of the housing 11. At its inner end, the shaft 40 is equipped with a diametrically extending key 42 adapted to seat within a transverse slot 43, in the end of a short shaft 44 which is mounted rotatably in a bearing 45 in the base plate 3 as observed by reference to Fig. 3. The inner end of the shaft 44 extends inboard beyond the bearing 45 and is equipped with a gear 46 which is in mesh with a gear 47 fixed coaxially

upon a cable winding drum 48 about which a steering cable as designated at 49, is wound.

The above described mechanism provides that, with the parts in normal position, as seen in Fig. 1, rotation of the drum in opposite directions, under influence of the steering cable, will cause the shafts 49 and 44 to be rotated accordingly and, through the gears 38 and 39, the shaft 32 will be rotated. This latter shaft, through the gears 39 and 31 will effect a rotary adjustment of the housing 8 about the axis of the supporting shank 8a, thereby to effect a desired directional application of propulsive forces also a desired adjustment of the rudder to effect the steering.

15 Referring again to Fig. 1, it will be observed, as a detail, that the mounting shank 8a of housing 8 is provided near its upper end with an encircling channel 50 in which keys 51 are fitted. These keys are enclosed within a flanged collar 52 which is threaded onto the lower end of the bearing 10, thereby to rotatably support the housing 8. It will also be observed that the outer end of the shaft 24 and the bearings 25 are supported in a cap 60 that is threaded or otherwise secured within an opening in the rear wall of the housing 11, which is alined with the shaft 24, so that removal of the caps will provide easy accessibility to the gearing contained within the housing 11.

20 In Fig. 3, it is shown that the upper end of the housing 11 is provided with an opening 64 over which a cap or cover plate 66 is fitted and which may be removed to give access to the gearing contained in the upper part of this housing 11.

25 It is apparent that, under the normal forward driving action of the propeller as imparted by the parts as seen in Fig. 1, the housing 11 engages flatly against the rear face of the plate 3 to effect a solid driving effect. It is apparent also that, should the rudder or propeller mechanism during forward travel of the boat strike an obstruction, it will be free to swing upwardly and rearwardly as to the dotted line position of Fig. 1, thus to avoid undue damage. However, in the event that the rudder forming housing 8 should be rotated through more than a predetermined angle from normal forward driving position, there will be the tendency to swing the 30 mechanism in a direction toward the dotted line position of Fig. 1. Such upward swinging would not be desirable in the event that rearward propulsion was desired. Therefore, I have provided a means whereby the housing 11 is automatically locked against upward hinging during a 35 reverse driving operation.

40 In Fig. 1, I have shown a locking pin 70 slidably mounted in a vertical guide 71 formed at the lower end portion of the plate 3. The lower end of the pin extends from the guide and adjacent the end is equipped with a nut 73 against which a coiled spring 74 acts to normally retain the pin in unlocked position. With the mechanism in normal driving position, the upper end of the pin 45 is alined with a socket 75 in the lower face of the casting 11. This arrangement of parts provides that should the pin be moved upwardly, its upper end will project into the socket 75 and thereby will lock the housing 11 against any swinging 50 movement toward inactive position.

45 For all normal forward propulsion positions of the propeller mechanism the parts are unlocked so as to insure against damage by reason of striking any obstructions, however, in order that the 55

pin may be moved to locking position after the rudder has turned beyond a certain predetermined angle from normal, I have provided a cam ring 80 which encircles the shank 8a coaxial thereto and is attached thereto by means of bolts, or the like, 82, as will be understood best by reference to Fig. 3. The top edge surface of the cam, through the greater part of its circumference, lies in a plane perpendicular to the axis of rotation. In the forward position of the cam is a depression 85 of uniform depth which extends through an arc of approximately 80°, symmetrically located with respect to the plane of the rudder and end of propeller shaft 7. The arrangement of the cam is such that the lower end of the locking pin at all times rides upon the top edge of the cam ring and normally rides in this depression of the cam with its upper end disengaged, or withdrawn from locking position. Upon rotation of the rudder in either direction beyond a predetermined extent the pin will then ride from the lower to the higher surface of the cam and its upper end will be moved into the socket 75, thereby to lock the parts in the position illustrated in Fig. 1. Thereafter the rudder and propeller mechanism may be turned to its extreme reverse driving position and will operate effectively in this position. However, as soon as turned back to normal position, the bolt moves to unlock the parts.

Referring now more particularly to Fig. 1, the rearward end of an engine driven shaft is designated at 90. This extends into a supporting bearing 91 coaxial of the hub portion 92 of a clutch drum 93; the hub being rotatably mounted in the bearing portion 5 of the casting 3. Mounted by this shaft 90 is a clutch device 95 adapted to be locked or disengaged with the complementary clutch member 93 to cause rotation of the latter to rotate the hub which at its inner end, has the driving gear 27 fixed thereon. The clutch is under control of a collar 98 that is shiftable on the drive shaft 90 and the sleeve, in turn, is under control of a lever 100, and a link 101 connected thereto and to a clutch shifting arm 102. The arrangement of the lever, and link and arm provides that, through this mechanism the collar 98 may be shifted to a position for causing the clutch to engage, and thus effect a driving connection between the engine shaft and the gear 27.

The ring gear 27 and the gear 26 which interlocks therein have particular forms of construction to permit of a ready disconnection when the housing 11 swings rearwardly and also to provide for interlocking engagement when the housing 11 swings back to normal position. The gear 27 is in the nature of an internal ring gear while the gear 26 is of the pinion type and small enough to easily interlock within gear 27. It also has the inner edges of its teeth beveled in a manner to permit an easy engagement with the teeth of the ring gear when the parts move back to driving position after being disengaged.

In order that the clutch may be shifted automatically to disconnect the driving mechanism in the event that an obstruction is encountered by the propeller or rudder, I have extended the link 101 beyond the arm 102 through a guide bushing 110 in the casting 3, and have continued it through an opening 112 in the upper end portion of the housing 11. At the end of the rod 101 is a housing 113 yieldably mounting a latch button 120 therein, as shown best in Fig. 2. The button is yieldingly held extended upwardly by

pressure of a spring 114 and is in position to be engaged by the top edge of the opening 112 in the plate when the housing swings rearwardly, thereby to shift the link rearwardly and to an extent sufficient to effect the disengagement of the driving clutch. After the housing has swung back to its normal position and the operator shifts the rod 101 to again set the clutch, the button will be depressed in passing through the opening 112 and thereby permit the rod to return to its normal set position. It will then snap to extended position as in Fig. 1.

It will be observed also by reference to Fig. 3 that the short shaft 44 is yieldingly mounted for longitudinal shifting in its bearing and that a coiled spring 146 normally urges it rearwardly into locking relation with the key on the inner end of shaft 40. In the event that the cross key 42 on the inner end of shaft 40 should not register with the slot in the shaft 42 when the housing 11 swings back to driving position, the shaft will yield and will operate to urge the shaft 44 into driving connection with shaft 40.

Drives of this character are applicable to the many types of motor boats, either of the small, row boat types, or of the larger cabin types. It may be made in sizes proper for the type of boat on which it is to be placed, and it provides for a reverse drive at the same speed of the forward drive. Furthermore, while the propeller mechanism is normally free for the upwardly swinging action to eliminate possibility of damage by reason of striking an obstruction, yet the propeller mechanism will be locked in operative position automatically incident to rotation beyond a normal forward driving angle.

Having thus described my invention, what I claim as new therein and desire to secure by Letters Patent is—

1. In a motor boat drive mechanism, a support for said mechanism adapted for a fixed mounting on a boat, a housing hingedly attached to the support for movement between propelling and inactive positions, a propeller, a mounting member for the propeller supported by the housing and rotatably adjustable for reversing the direction of propulsion relative to the boat, and a yieldable lock means movable to a position for locking the propeller mounting in rearward propelling position, and means on said rotatably adjustable propeller mounting member for moving the said lock means to locking position when the said member is adjusted to reverse propelling position.

2. In a motor boat drive mechanism, a support adapted for fixed mounting on a boat at the driving end, a housing hingedly fixed to said support for movement between propelling and inactive positions, a propeller mounting member supported in the housing and rotatable between positions for normal and reverse propulsion, a yieldable lock member whereby said housing may be locked against movement toward inactive position, and a cam on the propeller mounting, rotatable therewith to actuate the lock member to functional position incident to change in direction of propulsion beyond a predetermined angle relative to the normal direction.

3. In a motor boat driving mechanism, a mounting plate adapted for fixed mounting on a boat stern, a housing hingedly suspended therefrom and adapted to abut solidly against the base plate for forward propulsion of the boat and to swing rearwardly and upwardly to inactive position, a propelling and steering mechanism

mounted by said housing and rotatable therein about a vertical axis for changing the direction of propulsion relative to the normal line of the boat, and a normally released yieldable lock member for locking the said housing against swinging from forward propelling toward inactive position, a cam on the rotatable mounting for the steering and propelling mechanism for controlling the position of the lock and whereby it is automatically actuated to functional position incident to turning the propelling and steering mechanism to position for reverse propulsion.

4. In a motor boat driving mechanism, a base plate adapted for fixed mounting on the stern end of a boat, a housing hingedly suspended from the upper end of the plate and adapted to abut solidly against the plate for forward propulsion

of the boat and adapted to swing rearwardly and upwardly, a propelling and steering mechanism mounted by said housing and rotatable therein about a vertical axis for changing the direction of propulsion relative to the normal line of the boat; said housing having a downwardly opening socket therein, a locking pin slidable in the base plate, a shoulder on the pin, a spring acting against the shoulder normally to retain the pin retracted from locking position, and a cam fixed to and rotatable with the steering mechanism and adapted to engage the locking pin whereby the latter is automatically actuated to locking position incident to turning the propelling and steering mechanism to a position for reverse propulsion of the boat.

HARRY O. HEDGES.
